UNITED STATES PATENT OFFICE.

EMIL F. METZGER, OF PEORIA, ILLINOIS.

DESIGN FOR A BASIN.

46,533.

Specification for Design.

Patented Oct. 13, 1914.

Application filed July 25, 1913. Serial No. 781,245. Term of patent 14 years.

To all whom it may concern:

Be it known that I, EMIL F. METZGER, a citizen of the United States, residing at Peoria, in the county of Peoria and State of Illinois, have invented a new, original, and ornamental Design for Basins, of which the following is a specification, reference being had to the accompanying drawing, forming a part thereof.

Figure 1 represents a perspective view,

showing my new design in basins of elliptical shape, and Fig. 2 is a cross-section through the basin.

I claim:

The ornamental design for a basin, as shown.

EMIL F. METZGER.

Witnesses:

CHAS. W. LA PORTE,
FLORENCE STRUMPF.
